UNITED STATES PATENT OFFICE.

WILLIAM F. BAYER, OF BUFFALO, NEW YORK, ASSIGNOR TO CHASE & BAKER COMPANY, OF BUFFALO, NEW YORK, A CORPORATION OF NEW YORK.

SPOOL FOR MUSIC-SHEETS.

958,214.

Specification of Letters Patent. Patented May 17, 1910.

Application filed August 21, 1908. Serial No. 449,656.

To all whom it may concern:

Be it known that I, WILLIAM F. BAYER, a citizen of the United States, residing at Buffalo, in the county of Erie and State of New York, have invented a new and useful Improvement in Spools for Music-Sheets, of which the following is a specification.

This invention relates to the flanged rolls or spools upon which perforated music sheets 10 are wound, and more particularly to rolls of this kind in which one or both end-flanges are yieldable or adjustable lengthwise of the spool to compensate for variations in the width of the music sheet due to atmospheric 15 changes or other causes.

The object of my invention is the provision of an improved roll of this character in which the compensating device is neat and simple in construction and so organized as to 20 permit rewinding of the music sheet without binding or restraint of any kind.

In the accompanying drawings: Figure 1 is a side elevation of a music roll embodying the invention. Fig. 2 is an enlarged 25 longitudinal section thereof. Fig. 3 is an end view of the same. Fig. 4 is a transverse section in line 4—4, Fig. 2. Fig. 5 is a fragmentary longitudinal section of the roll, showing a modified construction thereof.

Similar letters of reference indicate corresponding parts throughout the several views.

A indicates the body of the roll or spool which latter may be either a music-roll or 35 a take-up roll. It preferably consists of a pressed-paper tube, but may be constructed of wood or other suitable material. In the ends of this tubular body are secured plugs B, preferably of wood, having reduced outer 40 portions b forming axial studs which project beyond the ends of the body. Driven into or otherwise secured to the ends of these studs are metallic journals c which are supported in the customary bearings not shown 45 in the drawings. If desired, the roll may be provided with other suitable or well-known means for journaling it in such bearings.

D, D¹ indicate the end flanges of the roll, one of which, say D, is rigidly secured upon 50 the adjacent stud b by driving or otherwise. The other flange D¹ is slidable lengthwise of the roll and mounted on a sleeve or thimble E surrounding the adjacent stud b upon which it is tightly driven or otherwise secured. The outer portion of the bore of the

flange D¹ is enlarged or recessed, as shown at d, while its contracted inner portion may contain a metallic bushing d¹ provided at its outer end with a flange d² which bears against the bottom of said recess. This 60 bushing is, however, non-essential and may be omitted, if desired.

Mounted on the thimble E and extending into the recess d is a cap preferably consisting of a collar f¹ having at its outer end an 65 inwardly-turned flange f which abuts against a projecting flange g at the outer end of the thimble. Between said collar and the flange of the bushing d¹ a spring h is interposed which surrounds the thimble E and is incased by said cap and the recessed roll-flange D¹. The collar f¹ is of sufficient width to extend into the recess d in all positions of the movable roll-flange D¹. 70

The spring h finds its abutment against 75 the collar f¹ which in turn abuts against the flange of the fixed thimble E and the pressure of the spring is exerted inwardly against the flanged bushing d¹ which practically forms an internal shoulder of the roll-flange 80 D¹. The latter is thus constantly pressed toward the opposite flange D, closely confining the music sheet between the flanges and causing it to track properly, while at the same time permitting the movable flange 85 to accommodate itself to variations in the width of the sheet.

When the music-roll is placed in its customary bearings, the pressure of the latter is not exerted against the flanges D, D¹ but 90 against the end of the stud b at the right hand end of the roll and the end of the journal c at its other end, and the roll is therefore free to rotate without binding both in taking up and rewinding the music sheet. 95

If desired, the flanged thimble and the cap may be formed in one piece, as shown in Fig. 5, E¹ indicating the thimble and f² the cap.

I claim as my invention:

1. A music roll provided at its end with a stud, a cap mounted on said stud and held against outward displacement thereon, a roll-flange mounted on said stud on the inner side of said cap and provided in its 105 outer side with a recess which receives the cap, and a spring arranged in said recess and said cap and bearing at its ends against the cap and the bottom of the recess.

2. A music roll provided at its end with a 110

stud, a sleeve mounted on said stud and having an abutment, a flange slidably mounted on the sleeve, and a spring interposed between the flange and said abutment.

5. A music roll provided at its end with a stud, a sleeve mounted on said stud and provided with a cap, a flange mounted on said stud and provided in its outer side with a recess which receives said cap, and a spring 10 arranged in said recess and bearing at its ends against the cap and the bottom of the recess.

4. A music roll provided at its end with a stud, a sleeve mounted on said stud 15 and having a projecting abutment at its outer end, a flange mounted on said stud and having the outer portion of its bore enlarged, forming a shoulder therein, and a spring surrounding said sleeve within the 20 enlargement of the flange-bore and bearing

at its ends against said shoulder and said abutment.

5. A music roll provided at its end with a stud, a sleeve mounted on said stud and having a projecting abutment-flange, a roll- 25 flange mounted on said stud and having the outer portion of its bore enlarged, forming a shoulder, a collar surrounding said sleeve and bearing against said abutment-flange, said collar having a rim which extends into 30 the enlargement of said flange-bore, and a spring applied to said sleeve between said collar and said shoulder.

Witness my hand this 19th day of August, 1908.

WILLIAM F. BAYER.
